UNITED STATES PATENT OFFICE

LEONARD L. RUGGLES, OF WHEATON, ILLINOIS, ASSIGNOR TO RESERVE HOLDING COMPANY, OF KANSAS CITY, MISSOURI, A CORPORATION OF DELAWARE

TELEPHONE SYSTEM

Application filed June 20, 1927. Serial No. 193,917.

The present invention relates to telephone systems in general, but is concerned more particularly with semi-automatic telephone systems, although certain of its features are not 5 confined specifically thereto.

The main object of the invention is the production of new and improved circuit arrangements whereby connections between manual lines entering an exchange may be set up by 10 automatic switches under the control of an operator at a switchboard in a remote exchange.

It is a further object of the invention to provide this service in an exchange terminating 15 lines of the local-battery magneto type without altering in any way the condition under which magneto lines operate when they terminate in the usual type of magneto manual switchboards.

20 The invention is especially suitable for application to a cluster of small villages and rural population centres, in which case several semi-automatic magneto exchanges may be each connected by one or more trunk lines 25 with an operating center, usually located in a town or city centrally located with respect to the area served by the several semi-automatic magneto exchanges.

The invention will be described hereinafter 30 as applied to a system including a semi-automatic magneto exchange having less than 100 lines terminating therein, there being a single operating trunk connecting the toll center with this office, over which trunk the operator 35 is automatically signalled when calls are made and over which she operates the automatic switches to complete desired local connections.

In order to provide for the setting up of 40 connections from the semi-automatic magneto exchange to other exchanges, or for setting up connections in the opposite direction, one or more toll trunks, in addition to the operating trunk, may be provided between the toll center 45 and the semi-automatic magneto exchange, which for convenience will be referred to hereinafter as a S.A.M.X.

A further object of the invention is the production of suitable circuit arrangements 50 whereby the seizing of a connector in the

S.A.M.X. and the releasing of the connector, after it has been operated under the control of the operator, are accomplished responsive to the initial ring and the "ring-off" of a magneto subscriber respectively. From this 55 it will be understood that a connector after it has been seized by an individual lineswitch responsive to the operation of the calling hand generator, maintains the lineswitch locked in operated position until the release 60 of the connector takes place when the calling subscriber again turns his hand generator, after he has replaced his receiver upon the termination of the conversation.

A further object of the invention is to provide a suitable finder switch for finding and connecting the operating trunk with any connector that has been seized. According to 65 a feature of the invention, a new and improved relay-type finder switch has been provided in place of a progressively-movable mechanism, owing to the fact that the finder must operate once for each call made, as a relay-type switch has a much longer life under heavy usage than a progressively-mov- 70 able mechanism.

A further object of the invention is the provision of suitable arrangements whereby either of the two toll trunks provided may be used in an emergency as an operating trunk 80 in case the operating trunk is defective or broken.

According to another feature of the invention, an emergency operating set is provided 85 in the S.A.M.X. so that an operator may control the automatic switches from that point during such times as all lines are down between the S.A.M.X. and the operating center, such as, for example, following a heavy sleet storm, or the like.

A further object of the invention is concerned with the provision of suitable arrangements at the power board in the S.A.M.X. for causing the finder associated 90 with the operating trunk to connect the operating trunk with the power board and give the operator a special signal in case an abnormal condition exists, such as, for example, a blown fuse, or the failure of the charging device to operate properly, etc.

According to another feature of the invention, suitable arrangements have been provided for automatically releasing a connection after it has been established a predetermined length of time. This is especially advantageous in view of the fact that subscribers do not always "ring off" when they are through conversing.

Another object of the invention is the provision of suitable arrangements whereby the operator at the toll center can operate either of the two toll connectors to complete a connection to any one of the local connectors to determine whether or not it is operated and to release the connector if it is in an operated position and not in use.

Another object is the production of suitable circuit arrangements whereby the operator can operate a connector and its associated code selector to cause ringing current to be sent back over the calling line, when the called substation is on the same line as the calling substation.

There are other objects and features of the invention which are mainly incidental to the carrying out of the objects and features above mentioned. The various objects and features of the invention can be understood best from a further perusal of the specification in connection with the accompanying drawings, comprising Figs. 1-8.

Referring now to the drawings, they show by means of the usual circuit diagrams a sufficient amount of equipment in a system embodying the features of the invention to enable the invention to be understood and carried into practice. Figs. 1-7 are circuit diagrams and Fig. 8 is a lay out of the sheet on which Figs. 1-7 are drawn, showing the way in which the sheet should be assembled in order that they may be understood best.

Fig. 1 shows an operating trunk and two toll trunks connecting the manual office on the left (used as the operating center) with the S.A.M.X. including the equipment shown on the right of Fig. 1 and in Figs. 2-7. It will be noted that part of the equipment at the manual exchange is at a toll board and part of it is at a local board. The operator at the toll board handles the toll connections with the S.A.M.X., and the operator at the local board handles the local traffic and also supervises the connectors in the S.A.M.X. periodically, to see that they are not left off-normal after being used. The equipment on the right-hand side of Fig. 1 is trunk-switching equipment used when necessary to switch the operating circuit from the operating trunk to one of the toll trunks in case the operating trunk is out of order.

Fig. 2 shows the relay-type finder and its auxiliary equipment associated with the operating trunk for the purpose of connecting the operating trunk to any local connector that is taken for use.

Fig. 3 shows the local connector No. 1, there being ten such connectors. This drawing shows also the line of substation A and the associated lineswitch LS, together with the master switch common to all the lineswitches. This drawing shows also a timing device individual to the associated connector for limiting the time during which the connector may remain operated.

Fig. 4 shows the wipers and a portion of the bank contacts of the local connector No. 1, together with the code selector CS1 individual to the local connector No. 1. This drawing shows also the substation B, accessible to the connectors.

Fig. 5 shows the toll connector No. 1 which terminates the toll trunk No. 1, Fig. 1. The bank and wipers of this toll connector are shown in Fig. 6, which shows also the code selector CS2 individual to the toll connector No. 1. This drawing shows also the code generator CG. This generator is a motor-driven drum, having a number of brushes and insulating and conducting segments as shown. The showing of the drum has been developed into a plane instead of a cylinder, in order that it may be understood better. The drum rotates in the direction indicated by the arrow.

Fig. 7 shows the power board and the associated power-supervisory relays. The power board includes the charging apparatus and the two storage batteries used to supply current for the operation of the apparatus in the S.A.M.X. It is to be noted that separate battery symbols and ground symbols are used throughout the drawings. It is to be understood that all ground symbols in the S.A.M.X. indicate a connection to the grounded bus bar 714 at the power board, and that all battery symbols indicate a connection to the battery bus bar 713. Fig. 7 shows also the emergency set in the S.A.M.X. This set is provided so that an operator may be despatched through the S.A.M.X. to control the switches through this emergency set, in case the lines are down between the S.A.M.X. and the operating center.

The apparatus having been described generally, a detailed description of its operation will now be given. For this purpose it will be assumed that the subscriber at substation A, Fig. 1, desires to converse with the subscriber at substation B, Fig. 4.

*Call from substation A, Fig. 3, to
substation B, Fig. 4*

In order to signal the operator at the operating center, the subscriber at substation A operates his hand generator to transmit ringing current over his line, after which he removes his receiver so as to be able to converse with the operator when she responds. Responsive to the ringing current, relay 302 operates and closes a circuit for the slow-

acting relay 301. Relay 301 operates and closes a circuit through the pull-down winding of the lineswitch. This circuit includes the open-main conductor which is common to all the lineswitches. This open-main conductor passes through certain contacts in the master switch and receives its current through the terminal 750. The two terminals 750 in Figs. 3 and 7 are joined together and the battery supplied to the open-main conductor is taken through the low-wound supervisory relay 727, Fig. 7, for a purpose to be explained hereinafter. When the pull-down winding 303 is energized, the plunger of the lineswitch is caused to enter the bank, and the cut-off armature is operated to disconnect relay 302 from in bridge of the calling line. When the contacts of the lineswitch are closed upon the entry of the plunger, a holding circuit is closed for the cut-off winding 304 of the lineswitch from the grounded release-trunk conductor 376, this conductor being grounded at the contacts of relay 313. This circuit is effective in maintaining the lineswitch operated after the slow-acting relay 301 has fallen back. As a further result of the plunger entering the bank, the talking conductors of the line are extended into connection with the corresponding conductors of the local connector No. 1, and ground from the grounded release trunk conductor 376 is extended through the lineswitch contacts to the combined lineswitch-hold and motor-switch test conductor 377 and through the master-switch wiper 343 for the upper winding of the master-switch test relay. A circuit is also closed over hold conductor 377 for relay 306 in the connector. Relay 306 operates and closes one point in the circuit of chain relay 341 in the master switch and places ground on the auxiliary test conductor 378, thereby closing a circuit for the lower winding of the test relay in the master switch. The master switch test relay operates from either winding and causes the master switch to advance in the usual manner to pre-select another idle connector. During the advance of the master switch, the connection between the exchange battery and the open-main conductor is held open in the usual manner.

As a further result of the grounding of the hold conductor 377, hold relay 307 operates and opens at its inner upper armature a point in the circuit of release magnet 321; at another upper armature, it grounds the local locking conductor 328; and at its lower armature it closes a circuit for relay 345 of the five-minute timing device for a purpose to be explained in detail hereinafter. As a result of the grounding of the locking conductor 328, a circuit is closed through the inner upper armature of relay 318 for relay 319. Relay 319 operates and shunts relay 319 for a purpose which will later appear.

As a further result of the operation of relay 307, it grounds the common start conductor 221 and the individual stop conductor 222 at its two upper armatures. As a result of the grounding of the start conductor, a circuit is closed for start relay 205, Fig. 2, of the relay-type finder. Relay 205 operates and places ground on locking conductor 219 at its lower armature, at its upper armature it connects the grounded interrupter 217 to the impulsing conductor 218. This impulsing conductor extends normally through the chain of contacts shown to relay 213. It may be pointed out at this time, that the relay pairs corresponding to connectors 2-9 are omitted in the drawing and that they are, in practice, included in the circuit between relays 209 and 210, at the point indicated by the dotted portion of the connecting conductors. As soon as interrupter 217 closes, relay 213 operates and locks itself through relay 212 to the locking conductor 219. Relay 212 does not operate immediately owing to the fact that it is short circuited through the interrupter 217. When the interrupter 217 opens, the initial circuit of relay 213 is broken, whereupon the locking circuit through relay 212 becomes effective and relay 212 operates, relay 213 remaining operated. When relay 212 operates it opens at its lower armature a point in the circuit of the non-operated relay 206, and at its upper armature it shifts the impulsing conductor 218 from relay 213 to relay 211. Relay 211 accordingly operates when the interrupter 217 closes the next time and it locks itself through relay 210, with the result that relay 210 operates as soon as the interrupter 217 opens again. Relay 210, it will be noted, opens the circuit of relays 212 and 213, whereupon these relays fall back.

This operation continues in the manner described until the common stop conductor 220 is connected by a relay similar to relay 211 or relay 213 to an individual stop conductor, such as conductor 222, which is grounded. Since the instant call is coming in over local connector No. 1, and since local connector No. 1 corresponds to relay 206 and 207, which are last to be operated, the operation continues until relay 207 operates following the operation of relays 209 and 208. When relay 207 operates, it locks itself to locking conductor 219 through relay 206 and the lower armature of relay 212, which relay was restored upon the operation of relay 210. As a further result of its operation, relay 207, at its lower armature, connects up the individual hold conductor 226 to the common hold conductor 231, and at its inner-lower armature it connects the individual stop conductor 222, previously grounded in the local connector No. 1, to the common stop conductor 220, thereby closing a circuit through the contacts of relays 204 and 203 for stop relay

201. Relay 201 operates and disconnects interrupter 217 from impulse conductor 218 at its middle upper armature, thereby stopping the transmission of impulses. This results in the opening of the initial circuit of relay 207, whereupon relay 206 operates in series with relay 207 and opens the circuit of relays 208 and 209, which fall back, and relay 208 transfers the impulse conductor 218 back to relay 213. As a further result of the operation of stop relay 201, it closes a circuit for relay 202 at its inner-upper armature, which circuit will be traced subsequently. At its upper armature relay 201 places a multiple ground on start conductor 221, and at its lower armature, it places ground on the common hold conductor 231, thereby grounding the individual hold conductor 226 through the lower contacts of relay 207. When this occurs a circuit is closed through contacts of relay 318, Fig. 3, for hold relay 309. Hold relay 309 operates and connects up the talking conductors 223 and 224 of the operating trunk to the corresponding conductors of the connector, at its upper and lower armatures. As a further result of its operation, relay 309, at its inner lower armature, prepares a circuit for the vertical magnet 326, and at its middle lower armature it opens the circuit of the relay 345 in the associated timing device for a purpose to be explained hereinafter.

In the operating-trunk equipment, Fig. 2, relay 202 now energizes in a circuit from the exchange battery through its winding, contacts of relay 201, mid-point of the left-hand repeating-coil windings, the two trunk conductors in parallel, contacts of the key EK, contacts of relay 121, inter-exchange portion of the operating trunk, contacts of the transfer keys TK2 and TK1, right-hand repeating coil windings in the operating center, contacts of the answering and release key 104, contacts of relay 102, and the winding of relay 101 to ground. When relay 202, Fig. 2, operates over this circuit, it opens a point in the impulse circuit at its lower armature and at its inner armature it closes a circuit for release relay 203. It prepares the impulse circuit at its lower armature; at its inner lower armature, it closes a locking circuit for stop relay 201 and opens its initial circuit; relay 204 responds to the closure of its circuit by relay 203 and opens a further point in the initial circuit of stop relay 201, for a purpose which will later appear.

In the operating center, relay 101, Fig. 1, pulls up in the line circuit above-traced over the operating trunk and through relay 202, Fig. 2, lighting the associated call lamp. When the operator notes the lighted condition of this lamp, she operates her key 104 into answering position, connecting the associated talking conductors to her telephone circuit. As a further result of being thrown into answering position, the key 104 connects

the common dialing conductor 105 to the operating leg of the operating trunk, at the same time disconnecting relay 101. Relay 101 now falls back and extinguishes the call lamp, the current flow over the operating trunk being continued through the calling device CD1. As a further result of the operation of key 104, a circuit is closed for relay 103, whereupon relay 103 operates and locks itself through release contacts of the key, closing at its upper armature a circuit for relay 102. Relay 102 operates and opens a further point in the circuit of relay 101, at the same time closing a circuit for the busy lamp.

The operator now converses with the calling subscriber and ascertains the desired number. Upon learning this number, the operator manipulates her calling device CD1 in accordance with the digits thereof. Upon reference to Fig. 4 it will be noted that the line of substation B terminates in the third set of contacts in the eighth level. The line number is therefore 83. It is assumed that code No. 5 is assigned to substation B, in which case the complete number is 83-5.

When the calling device CD1 is operated in accordance with the first digit 8, eight interruptions are produced in the circuit of relay 202, Fig. 2. As a result relay 202 falls back momentarily eight times. Each time it falls back, relay 202 grounds the impulse conductor 223 at its lower armature, thereby transmitting eight impulses of current over this conductor to the vertical magnet 326 of local connector No. 1, Fig. 3. The impulse path, at the time of its initial closure, includes contacts of relay 309, normally closed off-normal contacts, including spring 325, and relay 314. By the operation of the vertical magnet, the wipers 401-403 of the connector are raised step-by-step until they arrive opposite the eighth level of bank contacts. Relay 314 operates in response to the first impulse of current, and, being slow-acting, remains operated throughout the vertical movement. At its lower armature, relay 314 opens a point in the circuit of the rotary magnet 327 and prepares a new circuit for itself and for the vertical magnet which becomes effective upon the shifting of the associated off-normal contacts at the end of the first vertical step. When the first impulse is received, cut-off relay 309 is operated from two sources; its upper winding is energized from the upper contacts of series relay 314, and its lower winding is energized from off normal contacts 305 in multiple with the lower winding of chain-control relay 306. This double arrangement is provided to render more remote the chance of failure of the relay to operate. Upon operating, relay 310 locks itself to conductor 328 at its inner upper armature; prepares a release-on-busy circuit at its lower armature; and at its two uppermost armature removes

ground from start conductor 221 and stop conductor 222, leaving start conductor 221 grounded at the upper armature of relay 201, Fig. 2. The ungrounding of the stop conductor 221 prevents the reseizure of the connector by the operating-trunk equipment until the connector has been released and again seized by a lineswitch.

When the stop conductor is ungrounded, 10 relay 204, Fig. 2, falls back and closes a point in the stopping circuit of stop relay 201, now held operated by relay 203.

At the end of the vertical movement, relay 314 falls back and shifts the impulse conductor from the vertical magnet 326 to the 15 rotary magnet 327.

When the operator dials the second digit 3 in the number, three impulses are delivered over the conductor 225 to rotary magnet 327 20 of the connector through contacts of relay 309, normally-open off-normal contacts, lower armature, normal, of relay 314, and contacts of relays 315 and 317. By the operation of the rotary magnet, the wipers 401—403, Fig. 25 4, are rotated into engagement with the bank contacts terminating the line of substation B. Slow-acting change-over relay 316 is energized in multiple with rotary magnet 327 throughout the rotary movement. At its 30 upper armature, it disconnects the test-wiper conductor 354 from the upper winding of switching relay 317 and connects it instead, through contacts of relay 317, to busy relay 315, and at its inner lower armature it closes 35 a shunt around the corresponding contacts of busy relay 315 so as to prevent a premature opening of the rotary-magnet circuit in case test wiper 402 should encounter busy test contacts during the rotation of the connector and 40 thereby operate busy relay 315.

The operation taking place at the end of the rotary movement of the connector is dependent upon the busy or idle condition of the called line. Assuming first that the 45 called line is busy, test wiper 402 encounters a ground potential on the test contact of the called line, and busy relay 315 is energized over conductor 354 when the wipers of the connector come to rest. When relay 316 falls back under this condition, it completes a locking circuit for busy relay 315 to conductor 328 through the upper armature, operated, of relay 315; it opens the operating circuit at its inner lower armature; and at its lower 55 armature it connects the busy lead to the lower talking conductor through the lower contacts of relay 315. In this way the busy tone is transmitted to the operator over the operating trunk and to the calling subscriber over his line. Upon hearing this busy tone, the calling subscriber is expected to replace his receiver and call again later. When the operator clears out, the connector is released by the hereinafter explained operation of relay 313 when its circuit is closed at the middle 65

lower armature of relay 309. This circuit includes the lower armature of the operated relay 308 and a lower armature of the non-operated relay 317.

Assuming now that the line of substation B is idle when called, busy relay 315 is not operated when the wipers of the connector come to rest upon the contacts of the called line, and a circuit for the upper winding of relay 317 is closed at the upper armature of relay 316 when it falls back. This circuit extends from ground on the grounded locking conductor 328 through the upper armature normal, of relay 315, upper winding of relay 317, upper armature of relay 316, conductor 354, test wiper 402, test contact of the called line, and conductor 417 to battery through the cut-off winding of the lineswitch (not shown) belonging to the called line. This winding corresponds to cut-off winding 304 of the lineswitch LS, Fig. 3. The cut-off armature of the called lineswitch operates to remove the associate line relay from across the called line.

In the connector, Fig. 3, relay 317 operates 90 through its upper winding, and at its inner lower armature closes a locking circuit for itself to the grounded locking conductor 328. At another lower armature, it disconnects the operating conductor from rotary magnet 327 95 and extends it to conductor 355; at still another lower armature, opens a point in the circuit of the forced-release relay 313 so as to prevent a premature release when relay 309 subsequently falls back upon the disconnection of the operating trunk from the connector; it prepares a so-called ring-back circuit 100 at its lower-most armature through the associated condenser of small capacity; it opens a further point in the circuit of busy relay 105 315 at its inner upper armature; and at its upper armature it closes a direct connection between the grounded locking conductor 328 and the test-wiper conductor 354 so as to busy 110 the called line over a circuit path excluding its own upper winding.

Having set the connector on the contacts of the called line, the operator now dials the code-selecting digit 5 in order to operate the code selector CS1, Fig. 4, to select the code 115 assigned to substation B. When this last digit is dialed, five impulses of current are transmitted to the stepping magnet 409 of the code selector CS1 over conductor 355 and through series relay 406. In response to these 120 five impulses, the stepping magnet 409 of the code selector CS1 advances the wipers 411 and 412 step by step until they rest upon the fifth set of associated bank contacts. Relay 406 is maintained operated in series with the 125 stepping magnet of the code selector throughout its operation. At its inner armature, it shunts the inner contacts of off-normal relay 405 so as to maintain the operating circuit intact after the off-normal 405 operates 130

upon the first off-normal movement of the wipers of the switch. After the last impulse has terminated, relay 406 falls back and opens the operating circuit. A locking circuit for relays 407 and 408 is prepared at the lower armature of relay 405, and a pick-up circuit is now prepared through the middle armature of relay 405 and the lower armature of relay 406 for pick-up relay 407. Now, as soon as the code generator CG, Fig. 6, arrives in the position shown in the drawings, ground through the ground-feed wiper is placed on the pick-up conductor. This closes a circuit for pick-up relay 407 in the code selector CS1, Fig. 4. Relay 407 operates and locks itself through the lower armature of relay 405, at the same time opening its initial circuit. At its middle lower armature, relay 307 connects the common stop conductor to the individual stop conductor 356, preparatory to advancing the circuits from ringing position to talking position. As a further result of the operation of pick-up relay 407, ringing conductors 352 and 358 are connected up at the upper and lower contacts of this relay to the wipers 411 and 412, with the result that the code corresponding to the setting of these wipers is placed on these conductors and on the called line, as will be discussed subsequently.

Returning now to the operating center, Fig. 1, the operator, after having dialed the desired number waits only long enough to hear the so called ring back tone, which indicates that the line is being signalled, and then operates her key 104 into release position. In this position of the key, the operating conductor connected to the mid-point of the associated right hand repeating coil windings is connected back to the branch normally extending to ground through relay 101. This branch, however, is now open at the contacts of relay 102 and also at the contacts on the release key, as a result, line relay 202, Fig. 2, falls back and releases the connection between the operating trunk and the connector in a manner to be pointed out shortly.

Key 104, at its lower left contact, opens the locking circuit of slow-acting relay 103. Relay 103 falls back after a slight interval and opens the circuit of the slow-acting relay 102. Slow-acting relay 102 falls back after a slight interval and opens the circuit of the busy lamp at its lower armature, at the same time preparing a circuit for relay 101 at its upper armature. The operator now restores her key 104 to normal, as the operating trunk has been disconnected from local connector No. 1 in the S.A.M.X. during the time required for relays 103 and 102 to fall back, as will now be pointed out.

When relay 202, Fig. 2, falls back responsive to the opening of its circuit by key 104, Fig. 1, it again grounds the impulse conductor 225, but no operation is effected owing to the fact that this impulse conductor is open in

the code selector CS1, Fig. 4. At its inner armature, relay 202 opens a circuit for the slow-acting release relay 203, and relay 203 falls back after a slight interval and removes ground from impulse conductor 225 at its lower armature, at the same time opening the circuit of relay 201 at its inner lower armature. Relay 201 thereupon falls back and removes ground at its lower armature from the hold conductor 231. As a result of relay 201 falling back, the grounded interrupter 217 is again connected up through the upper contact of relay 205 to the impulse conductor 218. The operation of the relays of the finder is again started, but since the start conductor 221 is ungrounded at the upper armature of relay 201, relay 205 falls back immediately and stops the operation of the finder and releases the operated relays, unless start conductor 221 has in the meantime become grounded from another calling connector.

As a result of the removal of ground from the common hold conductor 231 by relay 201, ground is removed from the connected branch holding conductor 226, and hold relay 309 of the connector, Fig. 3, falls back and disconnects the talking conductors of the connector from the operating-trunk talking conductor 223 and 224 at its upper and lower armatures. At its inner lower armature, it opens a further point in the local branch of the operating conductor 225, and at its middle lower armature it again closes a circuit for relay 345 of the associated counting device, whereupon the device is again started to time the length of the conversation in a manner to be pointed out hereinafter.

Returning now to the established connection, the wiper 412 of the code selector CS1, Fig. 4, is now grounded and the wiper 411 is connected to the code conductor. There is a connection over the lower contacts of relay 407 and conductor 358 between the grounded wiper 412 of the code selector and the lower wiper 403 of the connector. This connection includes the lower armature, normal, of relay 318, and conductor 357. There is a similar connection between wiper 411 and the upper talking wiper 401 of the connector. This latter connection includes the upper contacts of relay 407, conductor 352, one of the upper armatures, normal, of relay 318, and conductor 353. As a result, the ringing current placed on the No. 5 code conductor is transmitted out to the called line over wiper 401 of the connector and it returns to ground over wiper 403. Upon referring to the code generator CG, Fig. 6, it will be noted that the code corresponding to conductor No. 5 is five rings. These five rings are preceded by a long warning ring. The reason for this arrangement is that the code is transmitted only once and the long attention ring is placed on the line ahead of the regular code so that the subscribers will all listen while the code is

being transmitted. The way in which this code, together with the long attention ring, is placed on the code conductor No. 5 from the associated ringing current source through the brushes of the code generator appears to be obvious from the drawings. It may be pointed out, however, that the conducting segments of the drum are not connected to any current source or connected together in 10 sets except as shown by the connecting conductors, indicated as being on the face of the drum. Actually, these conductors may be embedded within the drum instead of being on the face thereof.

15 After the last ring of the code has been delivered, the stop conductor is momentarily grounded when the last segment in its path is encountered by the stop brush on the code generator. When the stop conductor is 20 grounded, a circuit is closed through the middle lower armature of pick-up relay 407, Fig. 4, for stop relay 408. Relay 408 energizes and locks itself to ground through the lower contacts of off-normal relay 405. Release 25 magnet 410 is energized in multiple with relay 408 and in series with the low-wound supervisory relay 736, Fig. 7. When the release magnet operates, the code selector releases to normal position and off-normal relay 30 405 falls back and unlocks relays 407 and 408, also opening the release magnet circuit.

A circuit is completed (when the stop conductor is grounded) over conductor 356 for the ring-cut-off relay 318 of the connector, 35 Fig. 3. Relay 318 operates and locks itself to the grounded locking conductor 328 at its inner upper armature, at the same time opening its initial circuit and opening the circuit of slow-acting relay 319. At its lower armature and at one of its upper armatures, it disconnects the wipers 401 and 403 of the connector from the wipers 411 and 412 of the code selector CS1, and connects its wipers to the incoming talking conductors of the connector so as to complete the talking circuit to the called line. At its upper armature, relay 318 places the ring-off relay 320 across the upper and lower talking conductors of the connector, so as to place the release of the connector under the control of the calling line, and at another of its upper armatures it disconnects relay 309 from the holding conductor 226, whereupon relay 309 falls back and disconnects the talking conductors of the connector from the corresponding conductors

40 of the operating trunk in case the operator has not cleared out the circuit in the herein-before-described manner. When relay 320 is placed across the talking conductors by relay 318, it is short circuited by the contacts on slow-acting relay 319. Slow-acting relay 319 remains operated for an interval and maintains the short circuit around relay 320 for a sufficient time to permit any charge that 45 may be on the talking conductors of either

the calling or the called line to leak off before the short circuit is removed. This is specially valuable in case the ringer at the called substation has a condenser in series with it, in which case the condenser may have retained a charge at the end of the last impulse of ringing current transmitted to the called line.

When the subscriber at substation B responds to the code assigned to his substation 50 by removing his receiver, the conversation may take place in the usual manner.

When the conversation is terminated, the subscribers at substations A and B replace their receivers. The subscriber at substation A, being the calling subscriber, "rings off" by operating his hand generator momentarily in the usual manner. The momentary impulse of ringing current thus generated operates relay 320 of the connector. Upon operating, relay 320 closes a circuit from the grounded locking conductor 328 for slow-acting relay 311. Relay 311 operates and closes a circuit for the slow-acting relay 312. Relay 312 operates and prepares a circuit for 55 the slow-acting release relay 313, when the impulse of ringing current is terminated. Relay 311, which is slow-acting so as to enable it to hold up while relay 320 is vibrating in response to ringing current, now falls back and closes a circuit for relay 313 through the contacts of relay 312, at the same time opening the circuit of relay 312. Relay 313 operates and remains operated until relay 312 falls back, after which relay 313 again 60 restores. During the time that relay 313 is operated, ground is removed at the contacts of relay 313 from release trunk conductor 376. When this ground is removed, the current flow ceases in the bridge-cut-off and holding winding 304 of the lineswitch LS, in the upper winding of relay 306 of the connector, and in the winding of relay 307. When this occurs, the lineswitch LS releases and relay 65 307 of the connector falls back. Relay 306 remains operated for the time being due to the current flow through its lower winding from the off-normal contacts 405. When the lineswitch LS releases, the connection with release trunk conductor 376 is broken, so that 70 the private normal conductor of the line and the holding conductor 377 of the connector are not again grounded when ground is replaced on the release trunk conductor 376 by relay 313.

As a result of the deenergization of holding relay 307 of the connector, ground is removed from the grounded locking conductor 328, whereupon the locked-up relays 317 and 318 fall back. Relay 308 does not fall back 75 at this time owing to the current flow through its lower winding in multiple with the lower winding relay 306. As another result of the deenergization of relay 307, a circuit is closed at the inner upper contacts of this relay 80

through the associated off-normal contacts for release magnet 321, through terminal 753 and the supervisory relay 736, Fig. 7. By the operation of the release magnet, the wipers 401-403, Fig. 4, of the connector are restored to their normal positions in the usual manner, and the off-normal contacts of the switch are shifted back to their normal position, whereupon the circuit of release magnet 321 is opened. When the off-normal contacts 305, open, relays 306 and 308 fall back. Relay 306 renders the connector selectable again to the associated master switch by removing ground from test conductor 378 at its lower armature.

The connection is completely released and the apparatus involved therein is in readiness to be used in setting up other connections.

Reverting calls

It will now be assumed that the subscriber at substation A desires to call another subscriber whose substation is connected to the same line, the other substation being signalled by a code different than that of substation A. It will be assumed further that the local connector No. 1 is the one seized by the line-switch LS when the receiver is removed. That being the case, the connection is completed as before described between the operating trunk and the local connector No. 1 by the relay-type finder shown in Fig. 2.

When the operator responds and is informed that the calling subscriber desires to complete a connection to another substation on the same line, the operator sets the connector by dialing the digits 7 and 0 (the reverting call combination), after which she sets the code selector CS1, Fig. 4, in accordance with the code assigned to the called substation on the calling line. The operator requests the calling subscriber to replace his receiver and wait until the code of the called subscriber has been transmitted before removing the receiver again, as part of the ringing current would be shunted away at substation A otherwise, and also, disagreeable noises would be produced in the receiver by the ringing current.

It may be pointed out that the No. 70 local-connector bank-contact set are left without multiplying conductors to avoid interference in case two or more reverting conversations are carried on at the same time.

When the wipers are set on the "70" bank contacts, by impulses transmitted over conductor 225 under the control of the operator in the hereinbefore described manner, the "70" spring contacts 324 are closed, whereupon the reverting call relay 310 operates. Upon operating, relay 310 at its upper and lower armatures opens the talking connection between the operated connector and the operating trunk so as to prevent the ringing

current, to be applied subsequently, from reaching the operating trunk, in case the operator has not disconnected at the time the ringing current is applied. At its inner-lower armature, relay 310 prepares a circuit for relay 313 so as to enable the connector to be released at the termination of the ringing period.

As mentioned hereinbefore, the "70" contacts are left unmultipled. The "70" contact in the bank of test wiper 402, however, is connected to battery through a resistance so as to afford a circuit for the test winding of relay 317 when a reverting call is made. The corresponding contacts in the other connector banks are similarly connected to battery, each through a separate resistance.

When the connector has been set, relay 317 operates through its upper winding and through the test wiper 402, which encounters a battery potential on the contact on which it is set on account of the above mentioned individual resistance. Relay 317 performs a switching operation as hereinbefore described, including the switching of the impulse conductor from rotary magnet 327 to impulse conductor 355.

When the operator dials the code-selecting digit, the code selector CS1 is operated over conductor 355 in accordance with the code assigned to the called substation. At the end of the operation of the code selector, relay 406 falls back as hereinbefore described and connects up the pick-up relay, with the result that pick-up relay 407 operates and connects up the wipers 411 and 412 of the code selector. Following the operation of the pick-up relay, the ringing current is transmitted over conductor 352 from the wiper 411 and returns to ground over conductor 358 and wiper 412. Since the bank contacts on which the wipers 401 and 403 of the connector are standing are left dead, the ringing current does not take this path at this time. Instead, the ringing current passes through the upper and lower armatures of the reverting call relay 310 and thence back to the calling line, thereby operating all the ringers on the calling line.

After the ringing current has been transmitted, stop relay 408 of the code selector CS1 operates and locks itself in the hereinbefore described manner with the result that the code selector is restored to normal. At the same time, the hereinbefore-described impulse of current is delivered over conductor 356 to the ring-cut-off relay 318 of the connector, with the result that relay 318 operates and performs the switching operations hereinbefore described. At this time, since relay 310 is operated, a branch circuit is closed over conductor 356 through operated contacts of relay 310 and jumper 379 for release relay 313. Release relay 313 operates at this time and releases the connector in the hereinbefore described manner, leaving the two subscr-

ers on the line of substation A free to converse without having any central-office equipment tied up.

The calling subscriber, as well as the called subscriber, hears the code of the called subscriber and he removes his receiver after the code has been transmitted, with the result that the two subscribers may converse as soon as the called subscriber responds. The calling subscriber is instructed to not "ring off" at the termination of reverting calls, as this would operate the lineswitch LS and signal the operator needlessly.

It will be noted that the line of substation A is unguarded after the connector has been released and is therefore unguarded during conversation. In some localities, the subscribers object to this unguarded feature owing to the fact that a line is called occasionally while two subscribers are conversing in a reverting connection with the result that the line is intruded upon and with the further result that the application of ringing current while they are talking often results in very annoying noises in their receivers. In this case, arrangements are made so that the line remains guarded during conversation. This is accomplished by merely omitting the jumper 379, Fig. 3, in which case the release relay 313 is not operated upon the release of the code selector CS1 at the end of the application of ringing current. When this jumper is omitted, the subscribers are instructed to "ring off" at the end of reverting calls as well as at the end of other calls. The connector is then released at the end of the conversation in the hereinbefore manner.

Operation of timing device

In a system of this nature, it often happens that a subscriber finishes a conversation and leaves his telephone without "ringing off". In this case the connector is left operated and cannot be used by anyone else until it is released. In order to provide for the release of connectors left operated in this manner and in order to provide for the release of lineswitches in case a subscriber calls and receives no response from the operator, a timing device has been provided individual to each connector. A timing device individual to the local connector No. 1 is shown in Fig. 3 and is labeled 5-Minute timing device. This timing device is arranged to complete its operation and release a connection five minutes after it is started. This time of course is purely arbitrary and may be set at any other interval.

Assuming now that the connector shown in Fig. 3 is seized by a lineswitch such as LS, the holding relay 307 is operated over hold conductor 377 in the hereinbefore described manner, closing a circuit for relay 345 of the timing device through the "0"-level shaft contacts and the middle lower armature of re-

lay 309. Relay 345 operates and closes a circuit for stepping magnet 347 of the timing switch through the 30-second interrupter 346, common to the several timing devices. Every thirty seconds, this circuit is completed and opened again by the common interrupter with the result that stepping magnet 347 operates once each thirty seconds, advancing the wipers 350 and 351 one step each time it operates. Ordinarily, relay 309 is operated upon the response of the operator after the connector has been found by the finder shown in Fig. 2, whereupon the relay 345 falls back and releases the counting device by closing a circuit for release magnet 348 through the off-normal contacts 349. Assuming, however, that the call is not taken care of for some reason, the advance of the wipers 350 and 351 continues until wiper 350 reaches its tenth bank contact, at the end of approximately five minutes. When wiper 350 reaches its tenth contact, it closes a circuit for relay 313. Relay 313 operates and removes ground from release trunk conductor 376, whereupon the lineswitch LS restores to normal and relay 307 falls back. When relay 307 falls back it opens the circuit of relay 345, whereupon the timing device releases through the action of magnet 348, and relay 313 restores when its circuit is opened upon the release of wiper 350. The lineswitch LS remains restored until the calling subscriber rings again to make another attempt at securing the desired connection.

Assuming now that a connection has been extended by the lineswitch LS to the local connector No. 1 and that the operator has responded and operated relay 309, the relay 345 is released in the hereinbefore described manner, at the middle-lower armature of relay 309. The timing device remains at rest until the connector and the code selector have been operated and until the operating trunk has been disconnected from the local connector, at which point relay 309 falls back and again establishes a circuit for relay 345. Upon the operation of relay 345 the timing device operates one step every thirty seconds as before described. After the conversation has proceeded for approximately four minutes (assuming that the conversation lasts this long), wiper 351 comes into engagement with its eighth associated contact. This occurs at a time when stepping magnet 347 is energized, and the stepping magnet remains energized for a few seconds while the interrupter 346 is passing through its closed position. With the stepping magnet energized and with the wiper 341 on its eighth contact, a circuit is closed from the common warning-tone generator to the lower talking conductor. In this way, this tone is heard by the conversing subscriber and they are thereby warned that the connection will exist for only about another minute. It

will be noted that the warning-tone generator is merely a transformer having an interrupter for interrupting a battery circuit through its primary winding. The battery circuit is normally open and is closed only 5 momentarily at spaced intervals. The result is a succession of clicks which lasts for a few seconds while the interrupter 346 is stepping through its closed position. These clicks are not close enough together nor of sufficient 10 volume to interfere materially with the conversation. At the end of the closed period of the interrupter, magnet 347 falls back and opens the warning tone circuit.

15 If the connection is not released by the "ring off" before the timing device reaches its last position, the release is brought about by wiper 350 reaching its last contact and operating release relay 313. The lineswitch 20 LS is released as hereinbefore described and the connector releases responsive to the de-energization of relay 307, which closes the release magnet circuit at its inner upper contacts.

25 It may be pointed out at this time that the release of the connector stops the conversation by disrupting the connection in case a regular call between two separate lines is being made, but the subscribers may 30 continue to converse with one another if the call is a reverting call between two subscribers on the same line, the arrangement being intended more to free the equipment for use when it is being tied up due to subscribers 35 forgetting to "ring off" than to limit the conversation time, although the latter result is of considerable utility. It will be noted that a line is unguarded after the connector has been released by the timing device and that 40 subscribers on the same line who continue to converse run the risk of having their conversation intruded upon.

Two-number toll connection

45 The way in which calls between a S.A.M.X. line and an outside line are completed, will now be considered. These connections fall into two classes, depending upon the origin of the call. Considering outgoing connections, they fall into two groups, depending upon the distance over which it is desired 50 to converse. A connection set up to a line only a relatively short distance away is usually completed by the toll operator, while the calling subscriber waits for an answer, and is referred to as a two-number connection, while 55 connections to lines still farther away are set up by the operator who re-rings the calling subscriber after she has the connection ready.

60 Considering first a two-number connection, it will be assumed that the subscriber at substation A desires to converse with a subscriber outside of his local exchange whose line terminates in a nearby exchange. The subscriber 65 at substation A causes his lineswitch

LS to seize an idle connector, local connector No. 1, Fig. 3, for example, whereupon the operator is signalled in the usual manner. When the operator responds and asks for the number, the subscriber replies "long distance".

Upon learning that the calling subscriber 70 desires a long distance connection, the operator observes the condition of the busy lamps associated at her position with the toll trunks. If both toll trunks are idle, she may dial the 75 number assigned to either, but if one is busy, she dials the number assigned to the other toll trunk. If both toll trunks are in use, the operator informs the calling subscriber that "long distance" is busy.

Upon referring to Fig. 4, it will be noted 80 that the first and second sets of bank contacts in the tenth level of the local connectors are connected by conductors to the No. 1 and No. 2 toll connectors, respectively. In this case 85 it will be assumed that toll trunk No. 1 is idle and that the operator dials the number 01 assigned to this trunk. When she dials this number, the local connector No. 1, Fig. 3, responds in the usual manner and sets its 90 wipers 401-403, Fig. 4, on the first set of bank contacts in the "0" level, being the contacts to which the conductors 413-415 leading to toll connector No. 1 are connected.

Upon the shaft of the connector being 95 raised to the tenth level, the "0"-level shaft contacts 322, and 323, Fig. 3, are shifted. Contacts 322 remove the shunt from around the associated talking condenser for a purpose 100 which will become apparent as the description progresses. At contacts 323, a point in the circuit of the timing-device relay 345 is opened, as it is not desired to use this timing device in connection with outside calls, and a circuit is prepared by contacts 323 in their 105 shifted position for the lower winding of ring-cut-off relay 318.

When relay 316, Fig. 3, falls back at the end of the rotary movement of the connector and connects the test wiper conductor 354 to the ground through the upper winding of relay 317, relay 317 operates over test wiper 402 of the connector, Fig. 4, and over private normal conductor 414 extending to toll connector No. 1, Fig. 5. Relay 317 closes its 115 usual locking circuit and transfers the impulsive conductor to branch conductor 355 extending to the code selector CS1, Fig. 4.

The operator releases the operating trunk 120 from local connector No. 1, as before described, as soon as she has dialled the last digit 1 in the number assigned to the toll trunk No. 1. When she does so, and impulse of current is transmitted during the releasing operation over conductor 355 and operates the stepping magnet 409 one step during the time required for release relay 103, Fig. 2, to fall back after its circuit is opened by the impulsive relay 202. This operation 125 on the part of the code selector CS1 is merely 120

5 incidental, but as it does no harm it has been permitted to take place. Upon the termination of the impulse to the stepping magnet, relay 406 falls back followed by the energization of pick-up relay 407. The code corresponding to the No. 1 position of the code-selector CS1 is placed on wiper 411 and is extended back over conductor 352, but this ringing current does not reach the line owing to 10 the fact that ring-cut-off relay 318 is operated when relay 309 falls back, the circuit including the middle lower armature of relay 309, lower armature of relay 307, and springs 323, shifted. The code selector CS1 is released 15 in the hereinbefore described manner when the stop relay 408 pulls up.

When the test wiper 402, Fig. 4, is grounded at the end of the rotary movement of the connector, as hereinbefore described, a circuit 20 over conductor 414 is closed through the upper contacts of relay 507, Fig. 5, for relay 505, and a branch circuit is closed through the upper contacts of relay 503 for relay 501. This is the circuit, it will be remembered, over 25 which the upper winding of relay 317 is operated. The upper winding of relay 317 is short circuited in the usual manner to apply direct ground to the test wiper 402 as soon as relay 417 operates and locks itself at its inner 30 lower armature. When relay 505 operates, it switches the talking conductors associated with the right-hand repeating-coil windings from the talking conductors to the right to which they are normally connected and connects them instead to the incoming normal 35 talking conductors 413 and 415. At its inner armatures, relay 505 disconnects the impulse conductors connected to the inner left-hand repeating-coil terminals from line relay 506 40 and connects them instead to relay 514 for a purpose which will be apparent as the description progresses. When relay 501 operates over conductor 414 in multiple with relay 505, it grounds the lower conductor of 45 the toll trunk and connects ringing current to the upper conductor thereof, so as to apply ringing current to the toll trunk to signal the toll operator in the operating center. In order to terminate the application of ringing 50 current after a slight interval, relay 501 closes at its inner lower armature a circuit for the slow-to-pull-up relay 502. Relay 502 operates after a slight interval and closes a circuit for the slow-to-pull-up relay 503. Relay 503 operates and locks itself to conductor 414, at the same time opening the circuit of relay 501. Relay 501 falls back after a slight 55 interval and removes the ringing current from the toll trunk, at the same time opening the circuit of relay 502. Relay 502 falls back after a slight interval and opens the initial circuit of relay 503, leaving relay 503 locked to conductor 414.

In the operating center, relay 115, Fig. 1, 60 responds to the ringing current placed on toll

trunk No. 1 and repeated through the associated repeating coil windings, the lower winding of relay 115 being bridged across the talking conductors through contacts of cut-off relay 114. Upon operating, relay 115 locks itself through its upper winding and the upper contacts of the cut-off relay. A circuit for the call lamp at the toll board and for the one at the local board is closed in multiple with the locking winding of relay 115. 65 The operator at the local board does not ordinarily respond to the lighting of the call lamp on the toll trunk.

When the toll operator notes the lighted condition of the call lamp associated with the jack J2, she inserts the plug of an idle cord circuit into the jack, whereupon a circuit is closed through the upper springs of the jack for relay 113. Relay 113 is rendered slightly slow-to-pull-up due to the copper collar on its armature end as is denoted by the placing of the copper collar symbol on the upper end of the relay and by making the symbol black instead of shaded. When relay 113 operates, a circuit for the busy lamps and for cut-off 70 relay 114, whereupon the busy lamps become lighted and relay 114 operates and cuts off the lower winding of relay 115, at the same time deenergizing the upper winding of the relay and extinguishing the call lamps. Relay 113 75 also connects relay 112 through contacts of the dial key 117 to the impulse conductors connected to the inner terminals of the right-hand repeating coil windings. When this happens, relay 112 energizes through the right-hand repeating-coil windings and over 80 the toll line and closes a circuit for the associated supervisory lamp.

In the S.A.M.X. relay 514, Fig. 5, which is connected to the toll line through the inner 85 armatures of relay 505, contacts of relay 513, normal, and the left-hand repeating-coil windings, energizes in series with relay 112, Fig. 1. Relay 514 closes a circuit for the associated slow-acting relay 515, whereupon 90 relay 515 operates and prepares a circuit for relay 504 so as to enable the local connector to be released in a manner to be explained hereinafter.

After making a connection with the toll 95 trunk No. 1 through the jack J2, Fig. 1, the toll operator converses with the calling subscriber and learns from him the destination of the call. In addition to ascertaining the desired number, the toll operator enquires as 100 to the number of the calling substation so that the proper charge may be made.

After learning the desired number, the toll operator completes the connection to the called line through the upper plug of her cord circuit in any well known or desired manner; whereupon the conversation may take 105 place in the usual manner.

Inasmuch as the toll operator supervises 110 the toll connections rather closely and listens

in frequently to determine when the conversation has been finished, the subscribers may be instructed that it is unnecessary to "ring off" after a toll call, as the toll connector is provided with arrangements for releasing the local connector.

When the operator has listened in and has found that the conversation has terminated and that the subscribers have replaced their receivers, she withdraws the plug from the jack J2, Fig. 1, whereupon relay 113 falls back and opens the circuit of cut-off relay 114 and of the busy lamps. Relay 113 also opens the circuit of relay 112, whereupon relay 112 falls back and opens the circuit of the associated lamp. When the circuit of relay 112 is opened, relay 514, Fig. 5, which has been operated in series with relay 112 and over the toll trunk, falls back. Relay 514 opens the circuit of the slow-acting relay 515, and relay 515 falls back a moment later. During the interval required for relay 515 to fall back after its circuit is opened, a circuit exists through the upper contacts of relays 515 and 514 for relay 504, including the upper armature, normal, of relay 507 and the grounded private normal conductor 514. Relay 504 operates and places ground on normal conductor 413, at the same time placing battery 30 through a low resistance on conductor 415. When this happens, a circuit is closed through the talking wipers 401 and 403, Fig. 4, of the local connector No. 1, and over conductors 353 and 357 for the release control relay 320 through contacts of ring-cut-off relay 318. Relay 320 operates and initiates the releasing operation by closing the usual circuit for relay 311. The current flow over the calling line at this time is prevented by the condenser associated with the opened "0"-level shaft contacts 322. When relay 515 falls back it opens the circuit of relay 504, and relay 504 falls back after a slight interval and removes the battery and ground connections from conductors 413 and 415. When this occurs, relay 320 falls back and the release of the connection takes place in the hereinbefore-described manner. When the ground potential is removed from the private normal conductor 414 upon the release of local connector No. 1, relays 503 and 505, Fig. 5, which have been held operated over this conductor, fall back. The connection is now released and the apparatus involved therein may be used in setting up other connections.

Long-distance toll connection

It will now be assumed that the subscriber at substation A desires to converse with a subscriber located at a distance sufficiently great to bring the connection under the heading long distance. This call is initiated in the usual way and the local operator at the operating center dials the number 01 or the number 02, depending upon which of the toll

trunks is idle, for example the toll trunk No. 1 (No. 01), whereupon the connection is completed by the local connector, for example the local connector No. 1, to the toll trunk No. 1 in the manner hereinbefore described. The so-called "splash ring" is transmitted over the toll trunk No. 1 in the manner described hereinbefore to signal the toll operator. When the toll operator responds, the operations hereinbefore described take place and the calling subscriber is informed that he will be called back later, as the connection desired is a long distance connection that will require a certain amount of time to set up. The connection established with the toll operator is released in the hereinbefore described manner when the toll operator removes her plug from the jack J2, Fig. 1.

After the operator has extended a connection to the desired line or has made sure that she can do so, she inserts the plug of a cord circuit into the jack of an idle one of the toll trunks, the jack J2 for example, whereupon relay 113 is operated from the jack contacts and closes the usual busy-lamp and cut-off-relay circuit at its upper armature, at the same time connecting up relay 112 at its lower armatures to the impulsing conductors connected to the inner right-hand repeating-coil terminals. When this occurs, relay 112 operates over the toll trunk No. 1 and closes a circuit for the associated supervisory lamp.

In the S.A.M.X., line relay 506, which is normally connected to the toll trunk through the inner terminals of the associated left-hand repeating-coil windings, through the upper contacts of relay 513, and through the inner contacts of relay 505, operates in series with the calling supervisory relay 112, Fig. 1, and closes a circuit for release relay 507. Release relay 507 opens a point in the associated release-magnet circuit when it energizes and it prepares the usual operating circuit at its lower armature. At its middle upper armature, relay 507 grounds the local locking conductor 541, and at its upper armature it disconnects private normal conductor 414 from the local relays to which it is normally connected and connects it to ground instead, thereby rendering the toll trunk busy to the local connectors.

Having taken the toll trunk for use, the toll operator associates her calling device CD2 therewith by operating her calling device key 117. This key substitutes the circuit through the calling device CD2 and the release key RK2 for the branch circuit including relay 112. As a result relay 112 falls back when the dial key is thrown and the supervisory lamp is extinguished.

When the operator dials the first digit in the number of the calling substation, the circuit of line relay 506, Fig. 5, is interrupted a corresponding number of times. Relay 506 falls back each time its circuit is interrupted,

and, each time it does so, it transmits an impulse of current to vertical magnet 516, the circuit path over which the first impulse of current is transmitted including the lower armature, operated, of relay 507, the associated normally-closed off-normal contacts, and series relay 508. By the operation of the vertical magnet, the wipers 601-605, Fig. 6, are raised step-by-step until they arrive opposite the desired level of bank contacts.

10 The slow-acting series relay 508 operates when the first impulse is delivered and it remains operated throughout the vertical movement. Relay 508 serves to maintain its own circuit and that of the vertical magnet intact after the associated off-normal springs have shifted upon the first off-normal movement of the switch. At the end of the vertical movement, relay 508 falls back and transfers the operating conductor through the normally-open off-normal contacts to the rotary magnet 518.

When the operator dials the next digit, the rotary magnet 518 responds by rotating the wipers 601-605, Fig. 6, into engagement with the contacts of the calling line, which is being recalled. Relay 511 operates in multiple with rotary magnet 518 when the first impulse is delivered to the rotary magnet, 20 and, being slow-acting, remains operated throughout the rotary movement of the switch. At its inner upper armature, relay 511 disconnects the test wiper conductor 522 from the test winding of relay 512 and connects it instead to busy relay 510, and at its lower armature it places a shunt around the corresponding contacts of busy relay 510 so as to maintain its own circuit and that of the rotary magnet intact during the rotary movement in case busy relay 510 energizes due to 30 test wiper 601, Fig. 6, passing over grounded test contacts.

The operations taking place at the end of the rotary movement depend upon whether 40 the line being recalled has become busy in the interval or is still idle. If the line is busy, busy relay 510 is energized over conductor 522 and test wiper 601 at the end of the rotary movement, and when relay 511 falls back it completes the locking circuit of relay 510 to conductor 541, at the same time opening the impulsing circuit at its lower contacts to prevent further rotary movement. With the busy relay energized, a connection 50 exists between the lower talking conductor and the busy-tone lead through the lower contacts of the busy relay, and the upper talking conductor is grounded at the upper contacts of the busy relay, affording a circuit path for the flow of busy-tone current through the right-hand repeating-coil windings, thus giving the operator a busy signal.

Assuming now that the line is still idle, 60 busy relay 510 is not operated at the end of the rotary movement, and the falling back of

relay 511 is followed by the energization of relay 512 through its test winding, the lower terminal of the test winding being connected to the grounded locking conductor 541 through the contacts of busy relay 510, and the upper terminal winding being connected to test wiper 602 through contacts of relay 511 and over conductor 522. Relay 512 energizes through the bank contact on which wiper 602 is standing (such bank contact is omitted for convenience) and over the private normal conductor extending to the line-switch LS, Fig. 3. Accordingly the cut-off winding 304 of the lineswitch LS energizes and disconnects relay 302 from in bridge of the line, but the pull-down armature is not operated owing to the relatively low strength of the cut-off winding.

In the toll connector, Fig. 5, when relay 512 operates it locks its lower winding to the grounded conductor 541 at its inner lower armature; connects the grounded conductor 541 directly with the test wiper conductor 522 at the adjacent armature so as to place direct ground potential on the test wiper; transfer the impulse conductor at another of its lower armatures from the rotary magnet 518 through contacts of relay 513 to the branch conductor 525 leading to the code selector CS2; and at its upper and lower armatures it connects up over conductors 520 and 527 the talking wipers 601 and 603.

When the operator dials the code digit assigned to substation A, the impulses of current are transmitted over branch conductor 525 to the stepping magnet 610 of the code selector CS2 through contacts of relay 606 and through series relay 607. By the operation of the stepping magnet, wipers 612 and 613 are correctly positioned. Relay 507 is maintained operated throughout the last digit so as to maintain the stepping circuit intact after the off-normal relay 606 has operated upon the first step of the switch. At the lower armature of off-normal relay 606, a circuit is prepared for release magnet 611, and a locking circuit for relays 608 and 609 is prepared at the upper armature of relay 606, a pick-up circuit being prepared at the inner upper armature of said relay.

At the end of the digit, relay 607 falls back and opens the impulse circuit, at the same time closing another point in the pick-up circuit. When the code-generator CG reaches its pick-up position, ground is placed on the pick-up conductor, closing a circuit for pick-up relay 608, which relay operates and locks itself to the local locking conductor, at the same time opening its initial circuit. Relay 608 also prepares a circuit for stop relay 609 and connects up the wipers 612 and 613. The ringing current corresponding to the code assigned to substation A is placed on the line thereof during the further movement

of the code generator CG through the wipers 612 and 613 and over conductors 519 and 528, the path of the ringing current including the upper and lower contacts of relays 509 and 512 and the wiper conductors 520 and 527.

When the code generator CG reaches its stop position, stop relay 609 is operated over the stop conductor, locking itself to the locking conductor and opening its initial circuit.

10 At the same time, relay 609 disconnects the wipers 612 and 613 so as to prevent further application of ringing current. A branch of the stop relay circuit extends over conductor 521 to ring-cut-off relay 509 of the connector, with the result that ring-cut-off relay 509 operates and locks itself to the conductor 541, at the same time opening its initial circuit. At its upper and lower armatures, relay 509 15 disconnects the wipers 601 and 603, Fig. 6, from the wipers of the code selector and connects them instead to the portion of the talking circuit connected with the associated repeating-coil winding, thus completing the 20 talking circuit to the called line.

As soon as the subscriber on the line of 25 substation A responds, he may converse with the operator, and later with the desired called subscriber as soon as the operator has completed the connection between the two lines.

After the conversation has terminated, the operator releases the connection in the S.A.M.X. by withdrawing the plug from the jack J2, Fig. 1. When the plug is withdrawn, 30 relay 113 falls back and opens the holding circuit at its lower armatures, at the same time opening the cut-off-relay and busy-lamp circuit at its upper armature. When the holding circuit is opened, supervisory relay 112 falls 35 back and extinguishes the associated supervisory lamp, and the distant line relay 506, Fig. 5, falls back and opens the circuit of release relay 507. Release relay 507 falls back after an interval and removes ground from 40 locking conductor 541, whereupon the locked up relays 509 and 512 fall back. At its lower armature, release relay 507 applies ground through contacts of relay 506 to the release conductor 526, operating the release magnet 45 of the connector through the associated off-normal contacts and operating the release magnet 611 of the code selector over conductor 526 and through contacts of relay 606. The connector and the code selector are thus 50 restored to their respective normal positions. The circuit of the release magnet of the connector being opened at the associated off-normal contacts. When the code selector reaches 55 its normal position, off-normal relay 606 falls back and opens the circuit of release magnet 611 and unlocks relays 608 and 609. The apparatus in the S.A.M.X. is now completely 60 restored to normal, and may be used in setting up subsequent connections.

Incoming toll connections

An incoming toll connection, that is, a toll connection incoming to the S.A.M.X. is handled over either of the two toll trunks and through either of the toll connectors, the 70 operations being the same as those just described in connection with the recall of a calling subscriber by the toll operator.

Traffic supervision

The way in which the local operator at the operating center supervises the traffic and prevents the loss of calls due to connectors being falsely maintained busy, that is, not available for traffic, will now be explained. Referring to Fig. 3, it will be noted that there is a chain relay 341 mounted on the master switch and having a circuit including a separate pair of contacts in each of the ten local connectors, the contacts being on relay 306 in local connector No. 1 and on similar relays in the other connectors. Relay 306 operates over its upper winding when the connector is seized and it remains operated over its lower winding through off-normal contacts 305 until the connector is restored to normal. When the last connector has been taken for use, the chain relay 341 operates and disconnects battery from the associated open main conductor common to all the lineswitches such as LS, so as to prevent any more of them from plunging, and it disconnects both test wipers 343 and 344 from the test relay 342 so as to stop the operation of the master switch, as 95 further operation of the master switch at this time would be useless.

There is a normally-energized start relay 216, Fig. 2, the function of which is to signal the operator over the operating trunk, in a 100 distinctive manner, when all the connectors are in use. It might be supposed that this relay is operated from the chain relay in the master switch, but this is not the case, because it is unnecessary and undesirable to 105 give the operator the special signal until the last connector has been operated, whereas the master switch chain relay operates when the last connector has been taken for use. Relay 308, it will be remembered, operates from 110 either its lower winding or its upper winding, or from both, when the connector moves from its normal position, and it remains operated until the connector is released. This relay and the corresponding relays in the other 115 local connectors, control relay 216, Fig. 2, to bring in the special signal to the operator. Conductor 227 is normally grounded at each of the connectors at the upper contacts of relay 308 and the other relays corresponding 120 thereto in the other connectors, and remains grounded until the last of these relays have 125 operated.

Assuming that all connectors have been 130 seized and operated except local connector

No. 1 and that this connector is seized, chain relay 341 operates and performs the switching functions above mentioned. The operating trunk is connected with this local connector and the operator is signalled in the hereinbefore described manner. Now, as soon as the operator dials a digit so as to cause the connector to move from its normal position, the last remaining ground connection to conductor 227 is broken at the upper contacts of relay 308, whereupon relay 216, Fig. 2, falls back and makes a multiple ground connection to start conductor 224; grounds the alarm branch of stop conductor 220 at its inner lower armature; and prepares a connection between the lower talking conductor and the busy tone lead at its lower armature. Now, if a connector is not released before the operator has finished dialing the number and has freed the operating trunk, the relay type finder of the operating trunk starts operating again due to the start conductor remaining grounded at the upper armature of relay 216 after relay 201 falls back. When the operation is started, the counting relays 206 and 207 of the finder are locked up to conductor 219 through the lower contacts of relay 212, but the other counting relays are restored. Accordingly, relay 213 operates over impulse conductor 218 and through contacts of relays 208, 210, and 212, closing a locking circuit for itself through relay 212 and the lower contacts of relay 210 to conductor 219. Relay 212 does not operate for the time being owing to the fact that it is short circuited through the interrupter 217. Relay 213 also prepares at its lower armature a circuit for relay 214, and it closes at its inner lower armature a circuit for stop relay 201 by connecting stop conductor 220 to the branch grounded at the inner lower armature of relay 216. Relay 201 energizes when conductor 220 is grounded and disconnects the interrupter 217 at its upper armature, whereupon relay 212, being no longer short circuited, operates in series with relay 213 and unlocks relays 206 and 207 at its lower armature, at the same time extending the disconnected impulse conductor to relay 211 at its upper armature. Relay 201 also connects up relay 202 at its inner upper armature; disconnects the line relay of the test line switch at its inner lower armature; and at its lower armature it grounds the hold conductor 231, thereby completing the circuit of relay 214 through contacts of relay 213. Relay 214 grounds the lower associated talking conductor and connects the upper talking conductor through the associated small condenser to the busy-tone lead through the lower contacts of relays 215 and 216. As a result, the operator hears the busy tone when she responds to the usual signal brought in by the connecting up of the relay 202 by relay 201. Upon hearing the busy tone

on the operating trunk, the operator throws her key 104 into release position, bringing about the hereinbefore-described releasing action on the operating trunk by opening the grounded simplex circuit. The operator then restores her key 104 to normal and proceeds to check the connectors in the S.A.M.X. in a manner to be pointed out hereinafter. 70

When the operator releases the operating trunk by opening the simplex circuit through relay 202, Fig. 2, the equipment associated with the operating trunk clears out in the hereinbefore described manner, but it starts operating again and as soon as all of the relays have operated and relays 213 and 212 operate again stop relay 201 reoperates and signals the operator again because relay 216 remains deenergized, unless, of course, a connector has been released in the meantime. 75

Since it is quite likely that there are one or two local connectors off-normal and not in use due to the failure of the subscribers to "ring-off", the operator proceeds to make use of the provisions whereby she can listen in on the various connectors and release any one that may be off normal and not in use. 80

In order to do this, the local operator notes the condition of the busy lamp associated with the toll trunks at her switchboard. Assuming that the toll trunk No. 1 is idle as indicated by the non-lighted condition of the busy lamp, just above the jack J', the local operator may insert the calling plug of an idle cord circuit at her position into the jack J1. When the plug is inserted, a circuit is closed at the upper contacts of the jack for relay 111. Relay 111 operates and closes at its upper armature the usual busy-lamp and cut-off relay circuit, at the same time connecting up at its lower armatures the simplex conductors through contacts of key 116 to supervisory relay 110. Relay 110 operates and closes a circuit for the associated supervisory lamp. 95

In the S.A.M.X. line relay 506, Fig. 5, operates over the toll trunk and closes a circuit for release relay 507, with the result that the switch is prepared for operation in the hereinbefore-described manner. The supervisory conductors, such as 359-361, Fig. 6, of the local connectors terminate in the ninth level of the toll connector banks, local connector No. 1 being connected with the first set of bank contacts, local connector No. 2 being connected with the second set in the ninth level, etc. 100

After connecting with toll trunk No. 1, the local operator throws the calling device key 116, thereby disconnecting the simplex operating conductors from supervisory relay 110 and connecting them instead to the grounded calling device conductors. Having done this, the operator manipulates the calling device CD1 in accordance with the digit 9, thereby interrupting the current flow over the sim- 115

plex circuit of the toll line nine times. Each time the circuit is interrupted, line relay 506, Fig. 5, falls back and transmits an impulse of current to the vertical magnet 516. By the operation of the vertical magnet, the wipers 601—605 are raised opposite the ninth level of bank contacts. By the joint action of relay 508 and the associated off-normal contacts, the impulse circuit is transferred from the vertical magnet to the rotary magnet.

The operator now dials the digit 1, whereupon an impulse of current is transmitted to rotary magnet 518, with the result that the wipers 601—605 are rotated one step into engagement with the bank contact set in which conductors 359—361 terminate. Relay 515 is energized by relay 511 during the rotary movement. It is to be noted that all ninth-level bank contacts of the wiper 602 are connected together and are connected to the ninth-level bank contacts of wiper 605. This is to enable the converting relay 513, Fig. 5, of the connector to be operated when the wipers are rotated on the ninth level.

Although the local connector No. 1 is busy when the connection is completed through the No. 91 bank contact set, the busy relay 510 of the connector is not operated owing to the fact that the test wiper 602 is not employed for testing purposes at this time.

When slow-acting relay 511 falls back at the end of the rotary movement, it opens the circuit of slow-acting relay 515 and grounds test wiper 602 through the upper winding of relay 512. When this occurs, the upper winding of relay 512 is energized in series with the lower winding of relay 513 over conductors 522 and 524 and through wipers 602 and 605. Relay 512 locks itself to the locking conductor 541 and performs the switching operations hereinbefore described, and relay 513 locks itself to the same locking conductor 541 at its inner upper armature; and at its lower armature it disconnects the extended impulse conductor 525 leading to the code selector and connects it back to rotary magnet 518 so as to enable further rotation of the wipers to be effected. As a further result of the operation of relay 513, conductor 521 is grounded at the middle upper armature of the relay so as to operate ring-cut-off relay 509 to connect up the wipers 601 and 603.

As a further result of the energization of relay 513, it prepares at its inner-lower armature to ground the release conductor 523 extending to the release wiper 604, but the ground potential is not extended to conductor 523 and said wiper at this time owing to the fact that slow-acting relay 515 is still in an energized condition. As a still further result of the operation of relay 513, it disconnects the upper impulse conductor (coming from the inner terminal of the upper left-hand winding of the associated repeating coil) from line relay 506 and connects it in-

stead to relay 514. As a result, relay 506 remains operated over the lower trunk conductor and relay 514 operates over the upper trunk conductor and closes a new circuit for relay 515 before the said relay falls back.

The operator is now able to listen in on local connector No. 1, and she may release this connector if no conversation is heard after she has "challenged" the line, in the usual manner. Assuming that she hears a conversation going on, the operator merely dials the digit 1, whereupon another impulse of current is delivered to the rotary magnet of the connector through contacts of relays 512 and 513, whereupon the wipers are advanced another step. Assuming, however, that the operator hears no conversation going on and receives no answer when she "challenges", she releases the local connector by throwing her release key RK1, Fig. 1, into its left-hand position, removing ground from the upper trunk conductor, leaving the lower trunk conductor grounded through the calling device CD1. When the upper trunk conductor is ungrounded, relay 514 falls back, whereupon slow-acting relay 515 falls back after a slight interval and grounds conductor 523 through the associated contacts of relay 513. The ground potential applied to conductor 523 is extended by wiper 604 and the bank contact on which it is standing over conductor 360 to release relay 313 of the local connector, Fig. 3. When the release relay is energized, the local connector is released, in the hereinbefore-described manner, and relay 313 is deenergized again when ground is removed from conductor 360 responsive to the reenergization of relay 514, Fig. 5, by the operator when she restores the release key RK1.

When the connector is released, ground is replaced on conductor 227 at the upper contacts of relay 308, and relay 216 is energized again, whereupon ground is removed from the start conductor 224 and the associated locked up relays are deenergized responsive to the falling back of start relay 205.

After the operator has finished supervising or releasing a connector, she dials the digit 1 to effect a connection with the next connector. When the rotary magnet 518 responds to this digit, it advances the wipers of the switch another step, and relay 511 operates again in multiple with the rotary magnet. The operation of relay 511 at this time is merely incidental.

The operator supervises the second connector and then dials the digit 1 again in order to supervise the second, listening in on each connection and releasing all connectors that are needlessly remaining operated.

After the operator has advanced the toll connector No. 1, Fig. 5, onto the last set of bank contacts in the level and has supervised local connector No. 10, she releases the toll connector by removing the plug from the

jack J1, Fig. 1. Incidentally, she restores the dialling key 116. When the plug is removed, relay 111 falls back and opens the connection between both toll trunk conductors and ground at its lower armature, whereupon line relay 506, Fig. 5, and relay 514 both fall back. Relay 514 opens the circuit of relay 515, but relay 515 remains operated for an interval. Relay 506 opens the circuit of relay 507 and transmits another impulse of current to rotary magnet 518, whereupon rotary magnet 518 advances the wipers of the switch off the last set of bank contacts. Relay 511 is operated in multiple with the rotary magnet and closes a multiple holding circuit for relay 515. A moment later release relay 507 falls back and closes the circuit of the associated release magnet, at the same time unlocking relays 509, 512, and 513 by removing ground from the locking conductor 541. The rotary magnet circuit and the circuit of relay 511 are opened by the release relay 507 when it falls back, and relays 511 and 515 fall back shortly thereafter.

The connector is now completely released and may be used in setting up connections.

Power supply and supervisory apparatus

Referring now to Fig. 7, the apparatus shown therein, including the power board and the various control relays, will now be described. It will be noted that the batteries 711 and 712 which supply current to the bus bars 713 and 714 are supplied with charging current through the rectifier 707. The rectifier 707 is of the well known tungar-bulb type, the filament of the bulb being supplied with lighting current from the upper right-hand portion of the transformer winding.

The normal state of the apparatus is as shown in the drawings, with the marginal high voltage relay 726 energized, holding relay 725 energized. The arrangement is such that the charge is started each time a call comes in. It will be remembered that the terminal 750 is the terminal through which current is supplied to the open main conductor, common to all the lineswitches, such as LS, Fig. 3. This current supply is taken through the low-wound relay 727. The result is that, when a lineswitch is plunged, relay 727 operates momentarily and opens the circuit of relay 726. Relay 726 falls back and opens the circuit of relay 725. Relay 727 falls back again shortly after it pulls up and recloses the circuit of relay 726, but due to its marginal adjustment, relay 726 does not operate again until the charger has been started so as to bring the voltage of the battery up to its highest point, it being well known that a battery not receiving a charge is of lower voltage than one receiving a charge, even though the battery not receiving the charge is in a fully-charged stage. When relay 725 falls back, it closes at its upper contacts a

circuit for the heavy-duty relay 705, whereupon relay 705 applies the commercial power to the left-hand transformer winding causing the bulb 707 to light up and start to charge the battery. The charging current to the battery passes through resistance 708 around which the relay 709 is shunted. As a result, relay 709 operates and opens the circuit of relay 704 before this relay operates responsive to the closure of its circuit at the inner armature of the charge-starting relay 725. The charging current is delivered first to battery 711, and this battery receives the pulsating current just as it is rectified. Between the battery 711 and the "quiet" battery 712, there is an impedance 710, which smoothes out the current flow and enables the potential of battery 712 to remain constant.

When the voltage reaches the required amount, which time may be long or short depending upon the drain on the battery due to the operation of the switches following the plunging of the lineswitch, the marginal high voltage relay 726 reoperates and closes the circuit of relay 725. Relay 725 reoperates and opens the circuit of relay 705, at the same time opening another point in the circuit of relay 724. Relay 705 falls back and stops the charge. Relay 709 falls back and prepares a circuit for the alarm relay 724. The circuits remain in this condition until another call comes in when the charge is started again by relay 727.

It will be assumed now that a call comes and relay 725 falls back, but the charge fails to start. This may be due to a failure on the part of the commercial power or in the bulb 727, or possibly in the contacts of relay 765, or the transformer 706 may be burned out. At any rate, if the charge fails to start, relay 709 does not operate and the circuit for relay 724 remains closed. When relay 724 operates (after a slight interval) it closes a circuit for relay 723, whereupon relay 723 operates and places ground on conductor 754. Conductor 754 normally connected through contacts of relay 732 to conductor 757 is grounded and alarm relay 215, Fig. 2, operates. When relay 215 operates, it places ground on start conductor 224, prepares to stop the finder when relay 213 operates, by grounding the disconnected branch of the stop conductor 220 at its inner lower armature, and at its lower armatures it prepares to place ringing current through the associated small condenser on the upper talking conductor when relay 214 operates. The relay type finder is started into operation responsive to ground on the start conductor 224, and when relay 213 operates it prepares a circuit for relay 214 which is closed as soon as hold conductor 231 is grounded at the lower contacts of relay 201.

When the operator responds, she hears the distinctive tone caused by the placing of

ringing current on the line through the small condenser, which indicates to her that there is something out of order in connection with the power board or with certain of the other equipment as indicated by the supervisory relays. In order to discover just what the supervisory conditions are at the S.A.M.X., the operator releases the operating trunk in the usual manner and takes one of the toll trunks, for example the toll trunk No. 1, and dials the number 01. When the wipers of the toll connector No. 1 land upon the "01" contact set, Fig. 7, the ground potential on test wiper 602 through the upper winding of switching relay 512, Fig. 5, is placed on the test contact of the set, closing a circuit for the upper winding of relay 732, Fig. 7. Relay 732 operates and locks itself to conductor 754, at the same time removing ground from conductor 757 so as to restore the alarm relay 215, Fig. 2. As indicated by the note in the lower portion of Fig. 7, the "0" level contacts of wiper 602 are multiplied to the "0" level contacts (not shown) of wiper 605, Fig. 5. The result is that relay 513 now operates as hereinbefore described. The lower talking wiper 603 is grounded by the bank contact on which it is standing, and the upper wiper 601 encounters a contact which is connected through the lower contacts of relay 723 to the common ringing-tone signalling conductor 756 in case the charge alarm relays 723 are operated, as is now assumed. When the operator hears the tone with the connector set on contacts 01, she knows that the charge has failed to start, and a repair man may be dispatched to the S.A.M.X. to clear the trouble.

It may be that another case of trouble exists at the same time, and it is usually advisable for the operator to test the other trouble numbers, 02, 03, and 04, as a second alarm will not come in until the first case of trouble has been cleared.

In order to continue the test the operator merely dials the digit 1 causing the wipers of the toll connector to advance to the next set of contacts. The next set of contacts are associated with the fuse-alarm relays 728 and 729. In case a fuse blows, the spring contacts on the fuse make contact in the well-known manner with the fuse bus bar just below the main bus bar 713, closing a circuit to ground through the signal lamp 738 and the low wound relay 728. Relay 728 pulls up and operates relay 729 which closes a connection between the signal conductor 756 and the corresponding bank contact in the set 02. Accordingly, the operator hears the tone on this set if the fuse has blown.

In order to test the set 03, the operator dials the digit 1 again, whereupon the wipers of the connector advance another step. The set 03 has been assigned to the M.D.F. alarm. In case one of the so-called "heat coils" has

fused due to line trouble, the heat coil 731, for example, a ground potential has been placed on the associated common conductor, closing a circuit to battery through the signal lamp 739 and relay 730. Relay 730 operates and closes a circuit for relay 731 which connects up the upper 03 bank contact to signal conductor 756. The result is that the operator hears the ringing tone when the wipers are on the contact set 03 in case a heat coil has operated at the M.D.F.

Considering now the contact set 04, this contact set is associated with the release-signal relays 733-736. Each time a switch releases, the series supervisory relay 736 energizes due to the fact that current for the release magnet is supplied through this relay and through terminals 753, as indicated in various portions of the drawings, Figs. 3-6. Ordinarily, relay 736 operates only momentarily and falls back again as soon as the release operation has been completed. It happens occasionally that a switch does not release properly, and the release magnet circuit remains closed for an undue length of time. In this case, relay 736 remains operated long enough for an alarm to be brought in as will now be explained. When relay 736 operates, it connects ground through the lamp 720 to the lower armatures of relays 734 and 735. Relay 735 is energized from the pick-up lead through terminal 751 each time the code generator CG, Fig. 6, arrives in its pick-up position. If relay 736 is energized at this time, relay 735 locks up through the lamp 720 and the lower armatures of relays 735 and 736. If the relay 736 falls back before the device arrives in its stop position, relay 735 falls back and relay 734 is not operated. However, if relay 736 remains operated, relay 734 is operated through the upper contacts of relay 735 and through terminals 752 from the stop conductor when the code generator CG, Fig. 6, arrives in its stop position. When relay 734 operates, it locks itself through its lower winding in parallel with the lower winding of relay 735, and it closes a circuit for relay 733. The lower winding of relay 735 is of relatively high resistance, and the lamp 720 does not light through this lower winding. The lower winding of relay 734, however, is of relatively low resistance, and the lamp 720 now becomes lighted. Relay 735 may or may not fall back, depending upon its adjustment. Relay 733 connects up the common signalling conductor to the corresponding contact in the set 04, with the result that the operator hears the ringing tone on this set of contacts when she brings the wipers of the connector into engagement therewith. Having made the necessary tests, the operator may now release the connector. It will be understood, of course, that the toll connector No. 2 may be used in a similar manner.

It will be noted that each of the relays 729

and 731 and 733 is provided with contacts for grounding conductor 754 to operate the alarm relay 215, Fig. 2, over conductor 757 and through contacts of relay 732, Fig. 7. It will be noted further that relay 732, which is maintaining the alarm conductor 757 disconnected from the conductor 754, is locked up to conductor 754, so that in case the trouble which resulted in the grounding of conductor 754 is cleared or becomes clear without attention, conductor 754 becomes ungrounded and relay 732 falls back so as to be in readiness to bring in the next alarm. The operator may test at stated intervals after an alarm has been given to ascertain whether or not the condition has cleared itself. It may be pointed out that the lamps 737, 738, 739, and 740 are provided so that the particular trouble condition existing may be readily located when the repair man arrives. The key 722 is provided so that the buzzer 721 may be operated from conductor 754 as long as the trouble condition exists. This may be operated by the attendant when he arrives, and it may be restored again before he leaves so as to prevent unnecessary operation of the buzzer 121.

Using toll trunk as operating trunk

Since the control of the automatic switches is ordinarily carried out entirely over the operating trunk, Fig. 1, the entire S.A.M.X. is shown out of service in case the operating trunk breaks or becomes so defective that it cannot be used. If all trunks break, an operator may be dispatched to the S.A.M.X. to operate the exchange by means of the emergency set shown in Fig. 7, in a manner to be pointed out hereinafter. However, if the operating trunk breaks or becomes defective while one or both toll trunks are intact, either of the toll trunks may be used temporarily as an operating trunk. Assuming now that the operating trunk is defective somewhere between the two exchanges and that the operator desires to use toll trunk No. 1 temporarily as an operating trunk, the operator at the local board inserts the plug of a cord circuit into the jack J1, whereupon toll connector No. 1, Fig. 5, is prepared for operation in the usual manner. The operator now dials the number 09, whereupon the wiper 601—605, Fig. 6, are raised opposite the tenth level of bank contacts and are rotated into engagement with the ninth contact set. Referring to the lower right-hand corner of Fig. 1, it will be noted that no multiple exists between the "09" contacts in the bank of wiper 602 of toll connector No. 1 and the corresponding contact in the bank of wiper 602' of toll connector No. 2, while the "00" contacts in the bank of the test wipers of the toll connectors are multiplied together and are multiplied to the corresponding contacts in the bank of the test wiper of the local connectors. The reason for this arrangement will appear subsequently. When wiper 602 lands on its 09 contact, the ground potential placed on wiper 602 in the usual manner by the connector is effective in operating relay 124 through its lower winding. Relay 124 locks itself through contacts of relay 126 at its inner armature. At its upper armature, relay 124 closes a circuit for relays 122 and 121 in series. Relay 121 disconnects the operating trunks from the corresponding equipment in Fig. 2, and relay 122 disconnects the incoming conductors of toll trunk No. 1 from the toll connector No. 1, Fig. 5, and connects them instead to the operating trunk equipment, Fig. 2. When this occurs, the toll connector No. 1, Fig. 5, releases in the usual manner. In order to complete the switch over, the local operator removes her plug from the jack J1, permitting relay 111 to fall back, and she operates the transfer key TK1, Fig. 1, disconnecting the terminating equipment from the toll trunk No. 1 at its lower contacts, and shifting the operating trunk equipment at its upper contact from the defective operating trunk into connection with the toll trunk No. 1. The complete transfer of the toll trunk No. 1 into the position formerly occupied by the now defective operating trunk has been made, and the handling of calls over toll trunk No. 1 as an emergency operating trunk may now be proceeded with.

When the operator desires to resume the normal use of the operating trunk, she may use the other toll trunk and dial the No. 2 toll connector up to its "00" contacts, whereupon relay 126 is operated through test wiper 602' and unlocks relay 124. This switches the S.A.M.X. end of the operating trunk and of the toll trunk No. 1 back to their normal state, while the operator takes care of the manual end by restoring the transfer key TK1. In case the toll trunk No. 2 is not available for performing the switching-back operation, the operator may use one of the local connectors. This is done by dialing the first connector over which a call is made up to the "00" contacts to operate relay 126, the calling subscriber being requested to hang up and call again later. As an alternative, the operator may operate the ringing-control key 176 at her position, whereupon the associated relay applies ringing current to the operating trunk conductors, now connected to toll trunk No. 1, whereby the ringing current is transmitted through the repeating coil shown in Fig. 2 to the test line switch to which the labeled conductors extending upward in Fig. 2 extend. This lineswitch operates and takes one of the local connectors for use, whereupon the operating trunk is automatically connected to this connector in the usual manner and the operator dials this connector up to the 00 contacts, thereby operating relay 126, Fig. 1. The operating trunk is thereby transferred back at the S.A.M.X. end, and the

operator restores the transfer key TK1, Fig. 1. The operator may now operate the key 176 again, and again project ringing current over the operating trunk and thereby release the test lineswitch and the operated connector. It may be mentioned at this time that the operator may operate the test lineswitch at any time to bring in a call and thereby test the operation of the equipment to ascertain whether or not it is working properly.

Emergency operation

Assuming now that all lines are down between the operating center and the S.A.M.X., for example, following a sleet storm or heavy wind storm, an operator may be despatched to the S.A.M.X. to operate the switches at that point. Upon arriving at the S.A.M.X., the operator operates the emergency key EK, Fig. 1, transferring the S.A.M.X. end of the operating trunk to the emergency set shown in Fig. 7. With this key so operated, calls arriving at the operating trunk come in on the emergency set, line relay 703 being connected through contacts of the answering and release key to the simplex conductor of the extended operating trunk. When a call comes in relay 703 operates in series with impulsing relay 202, Fig. 2, lighting the associated call lamp. When the emergency operator responds by throwing her key into answering position, the simplex dialing conductor is transferred to the calling device CD³, and relays 701 and 702 are operated in a manner corresponding to the operation of the similar relays shown in Fig. 1 and normally associated with the operating trunk. The operator controls the switches in the usual manner, and she releases the operating trunk equipment by throwing the key into release position.

In order to take care of night operation, when the operator may retire for a few hours of sleep, the key 704 may be operated, in which case the buzzer 721 is operated at the lower contacts of line relay 703 when a call comes in, thereby awakening the operator.

After the lines have been repaired, the emergency set is disconnected and the regular operating trunk is connected up, upon the restoration to normal of the key EK, Fig. 1.

Referring now to Fig. 2, it may be pointed out that the arrangement is such that the relay-type finder does not start hunting from its normal position in case one or more other calls are waiting when a connection is released between the operating trunk and the local connector. Instead, the locking conductor 219 is maintained grounded by start relay 205 so that the endless-chain operation of the interlocked relays 206-213 starts again and from where it left off continues. It may be well to point out at this time that the finder is arranged to hunt from connector No. 10 to connector No. 1 instead of in the

opposite direction, which would appear to be the more natural order, on account of the purely arbitrary direction in which standard master switches are arranged to hunt. The finder hunts for the connectors in the same direction as the master switch does. This insures that the calls will be handled more nearly in the order in which they arrive at the exchange.

Referring now to Figs. 2 and 3, a special arrangement in connection with the relay type finder, shown in Fig. 2, will now be discussed. It will be remembered that the finder is caused to start and connect with a local connector, such as the local connector No. 1, responsive to the operation of relay 307, and that relay 308, by removing ground from conductor 222 conditions the circuits so that the finder will not again stop on this connector until it has been released and reseized. It will thus be apparent that it is very important that relay 308 operate in each case so as to enable the finder to operate properly without interference from the operated connector. In spite of the double circuit arrangement provided for operating relay 308, it may happen occasionally that this relay or one of the other similar relays in another connector fails to operate, due for example to burned out windings or to dirty contacts. In order to minimize the effect of such a condition, relay 204, Fig. 2, has been provided to open a point in the circuit of relay 201 in case conductor 220 remains grounded from a branch conductor, such as 222, after the corresponding connector has been operated. In case relay 204 remains operated due to continued grounding of conductor 220, relay 201 is permitted to fall back when relay 203 restores, and the operation of the finder is allowed to proceed until relay 204 falls back and reconnects conductor 220 to relay 201. By this time, conductor 220 will have been disconnected from the defective branch such as 222 by the restoration of the corresponding relay, such as 207, and the finder may proceed to locate and connect with a connector other than the defective one. Of course, the defective connector will be a source of annoyance, as the finder will stop on it again as soon as it has reached that point again but the arrangement prevents the defect from completely disabling the exchange pending the clearing of the trouble.

Since relay 204 must be made slow-acting in order to enable it to remain operated long enough to permit the next set of relays to operate and restore the previously-operated pair, it may happen that the finder is advanced more than one relay group before relay 204 falls back and permits the stopping operation to take place. In order to avoid the necessity of a critical adjustment on relay 204 and at the same time to permit the finder to stop, ordinarily, on the connector next in order, relay 204 is arranged to energize from

conductor 220, with the result that it will not energize and interfere with the operation of the finder except in those rare instances when conductor 220 remains grounded as pointed out above.

5 What is claimed is:

1. In a telephone exchange system, magneto lines entering an exchange, trunk lines in said exchange, switching apparatus in said exchange, ringing current generators on said lines, and means responsive to the operation of the ringing current generator on a calling line for operating said switching apparatus to connect such line with an idle one of said 10 trunk lines, said means including a slow acting relay individual to such line, and a holding circuit automatically effective upon the establishment of the said connection for maintaining the said connection independent 15 of further current flow over the last named line.

2. In a telephone system, a telephone exchange terminating metallic magneto lines of the local-battery type, automatic switching 20 mechanism in said exchange, and means including operator signalling and operator controlled means for effecting and releasing connections between said lines including said mechanism and exclusive of manual switching equipment, while maintaining said lines free of holding current and ground connections.

3. In a telephone system, a telephone exchange terminating metallic magneto lines of the local-battery type, automatic switching mechanism in said exchange, and means including operator signalling and operator controlled means for effecting connections between said lines including said mechanism 25 and exclusive of manual switching equipment, while maintaining said lines free of direct-current flow and ground connections.

4. In a telephone system, an automatic exchange terminating local-battery magneto 30 lines, trunk lines in said exchange, means responsive to ringing current transmitted to said exchange over a metallic circuit including the two conductors of a calling line in series for effecting a connection between such line and one of said trunk lines, an operator's switchboard, means responsive to the seizure of said trunk line for signalling the operator thereat, automatic switching mechanism controlled by said operator over the seized trunk 35 line to complete a connection from the calling line to a desired called line, and means for releasing said connection responsive to further transmission of ringing current to the exchange over the calling line.

5. In a telephone system, a telephone exchange, trunk lines therein, subscriber lines entering the exchange, an operator's switchboard, an operating trunk extending from said exchange to said switchboard, a relay-type finder connected to said operating trunk

and having access to said trunk lines, means controlled over any calling line for effecting a connection between such line and an idle one of said trunk lines, and means for operating the relays of said finder successively to 70 test for and connect the operating trunk with the particular selected one of said trunk lines.

6. In a telephone exchange system, a telephone exchange, a plurality of local-battery magneto lines entering said exchange, trunk lines within said exchange, an operator's switchboard located at a remote point, an operating trunk connecting said switchboard and said exchange, a relay group containing a separate trunk-connecting relay 75 for each of said trunk lines within said exchange, means responsive to ringing current transmitted to said exchange over a calling one of said magneto lines for effecting a connection between such line and an idle one of said trunks, and circuit arrangement responsive to the closing of such connection for operating the required relay of said relay group to effect a connection between said operating trunk and the particular idle 80 trunk taken for use.

7. In a telephone system, a remotely controlled semi-automatic exchange, an operating point, an operating trunk connecting said operating point and said exchange, a toll 95 trunk also connecting said operating point and said exchange, operating-trunk equipment in which said operating trunk terminates in said semi-automatic exchange, and means controlled over said toll trunk for disconnecting said operating trunk from the associated operating-trunk equipment and for operatively connecting said toll trunk to said equipment.

8. In a telephone system, a remotely controlled semi-automatic exchange, an operating point, an operating trunk connecting said operating point and said exchange, a toll trunk also connecting said operating point and said exchange, operating-trunk equipment in which said operating trunk terminates in said semi-automatic exchange, means controlled over said toll trunk for disconnecting said operating trunk from the associated operating equipment and for operatively connecting said toll trunk to said equipment, and means for bringing about a similar switching operation, as regards the operating trunk and toll trunk, at the operating point.

9. In a telephone system, a remotely operated semi-automatic exchange connected with an operating point by an operating trunk, said operating trunk being provided with equipment at the operating point to enable the operator thereat to answer calls originated in the semi-automatic exchange and to operate the switching equipment in said semi-automatic exchange over said operating trunk to complete desired connections,

an operating equipment in the semi-automatic exchange in which said operating trunk terminates, an emergency operating set in the semi-automatic exchange containing a duplicate of said equipment at the operating point, and switching means for disconnecting said terminating equipment from the operating trunk and for connecting it instead to said emergency operating set whereby the semi-automatic exchange may be operated locally during such times as the operating trunk is out of order.

10. In a telephone system, a remotely operated semi-automatic exchange connected by an operating trunk with an operating point, terminating equipment in said semi-automatic exchange, a repeating coil between said equipment and said operating trunk, an emergency operating set arranged to enable the semi-automatic exchange to be operated locally through said set, and switching means for connecting said operating set to the terminating equipment through said repeating coil and for disconnecting said operating trunk therefrom.

11. In a telephone system, a telephone exchange, a line terminating therein having a finder switch connected thereto, trunk lines accessible to said finder switch, a power board in said exchange, tone conductors associated with said power board and accessible to said finder, and means responsive to any one of a plurality of abnormal conditions in the exchange conditions in the exchange for causing said finder to effect a connection with said tone conductors.

12. In a telephone system, a telephone exchange, a distant supervisory point, an automatic switch in said exchange controlled over a line extending to said exchange from said supervisory point, separate positions of said switch being assigned respectively to separate abnormal conditions which may arise in said exchange, means for notifying an operator at said operating point in case any one of several abnormal conditions exist, and means under control of the operator for operating said switch successively to said positions, and signalling means associated with said positions so as to give the operator a distinctive signal when the switch is in a position corresponding to an existing abnormal condition.

13. In a telephone system, a semi-automatic magneto exchange having switches therein for completing local connections between magneto lines, means under the control of an operator at a distant point for setting said switches to effect connections, a toll line extending from said distant point to said exchange and terminating in a toll switch, and means responsive to operator control over said toll line for bringing said toll switch into association with the local switches

successively and for releasing any operated switch which is not in use.

14. In a telephone system, a telephone exchange, lines terminating therein, a switch having access to certain of said lines, means for operating said switch to extend a connection from a calling one of said lines to a called one of said lines and for applying ringing current from said switch to the called line, and means responsive to the actuation of said switch into a different position for effecting a switching operation so that the ringing current is transmitted back over the calling line to signal a called substation on the calling line.

15. In a telephone system, lines, a finder having access thereto, means for placing any line in a calling condition, means responsive thereto for causing said finder to advance to said line and to stop thereon, and means subsequently effective for causing said finder to automatically advance to another line in calling condition while said first line remains in calling condition.

16. In a telephone system, lines, a finder having access thereto, means for placing any line in a calling condition, means including testing means causing said finder to advance to said line and to stop thereon, means controlled through said finder for advancing said line from its calling condition and for subsequently causing said finder to advance under the control of said testing means to another calling line, and means for disabling said testing means temporarily to enable said finder to pass beyond any line that fails to advance out of its calling condition.

17. In a telephone system, lines, a finder having access thereto, means for placing any line in a calling condition, means including testing means causing said finder to advance to said line and to stop thereon, means controlled through said finder for advancing said line from its calling condition and for subsequently causing said finder to advance under the control of said testing means to another calling line, and means for disabling said testing means temporarily to enable said finder to pass beyond any line that fails to advance out of its calling condition, said disabling means being effective only in case a line fails to pass out of its calling condition.

18. In a telephone exchange system, magneto lines entering an exchange, line switches individual, respectively, to said lines, trunk lines accessible to said line switches, ringing-current generators on said lines, and means responsive to the operation of a ringing-current generator on a line for transmitting ringing current to the line switch over the two conductors of the lines in series, and means in the line switch individual to such line for operating the line switch to extend a connection to an idle one of said trunk lines.

19. In a telephone exchange system, mag-

- neto lines entering an exchange, trunk lines in said exchange, switching apparatus, ringing-current generators on said lines, and means responsive to the operation of a ringing-current generator on a line, and including a relay in the exchange bridged across the two talking conductors of such line, for operating said switching apparatus to connect the corresponding line with an idle one of said trunk lines. 5
- 10 20. In a telephone system, a two-conductor line terminating in a line switch, a relay bridged across the conductors of said line and responsive to ringing current received over said line, a slow acting relay controlled by the first relay to operate said line switch, and contacts on said line switch for opening the bridge containing said relay upon the operation of the line switch. 15
- 20 21. In a telephone system, a line terminating in a line switch, a relay responsive to ringing current received over said line, a slow acting relay controlled by the first relay to operate said line switch, a holding circuit for said line switch completed upon said operation, and means responsive to further ringing current received over said line for opening said holding circuit. 25
- 20 22. In a telephone system, a first line and a second line, non-numerical switching means, means responsive to ringing current received over the first line for operating said non-numerical switching means to connect the two lines together, a holding circuit for said non-numerical switching means for maintaining it operated, said holding circuit including a normally-closed contact pair, and means responsive to further receipt of ringing current over the first line for releasing said connections by opening said normally closed contact pair. 30
- 20 23. In a telephone system, a first line and a second line, non-numerical switching means for connecting said lines together, means responsive to ringing current received over the first line for operating said non-numerical switching means to connect the two lines together, a holding circuit for said non-numerical switching means for maintaining it operated, and a normally closed contact pair in the second line included in said holding circuit. 35
- 20 24. In a telephone system, means responsive to ringing current received over one line for closing one portion of a connection from such line to another line, automatic switching mechanism for completing the connection to said other line, and means in said automatic switching mechanism responsive to ringing current received over a metallic circuit for releasing said connection. 40
- 20 25. In a telephone system, means responsive to ringing current received over one line for closing one portion of a connection from such line to another line, automatic switching 45
- mechanism for completing the connection to said other line, and means in said automatic switching mechanism responsive to ringing current received from the first line over a metallic circuit for releasing the connection between the two lines. 70
26. In a telephone system wherein connections involving magneto lines are set up through automatic switches, means in an automatic switch used in establishing a connection involving a magneto line for preparing to release such automatic switch responsive to an application of ringing current from a magneto line, and means responsive to the cessation of ringing current for releasing the automatic switch. 75
27. In a telephone system, local automatic switches arranged to complete connections from subscribers' lines entering a telephone exchange, a trunk line incoming to said exchange and terminating in an incoming automatic switch, trunk connections whereby monitoring connections may be extended through said incoming switch to said local switches whether they are busy or idle, and trunk connections whereby said local switches may extend connections to said incoming trunk line. 80
28. In a telephone system, local automatic switches for setting up connections from local lines entering a telephone exchange, a toll line incoming to said exchange and terminating in a toll switch having access to said local switches, and means including local trunk connections whereby any local switch may seize said toll line. 85
29. In a telephone system, local switches arranged to extend connections from local lines entering a telephone exchange, a toll line entering said exchange and terminating in a toll switch having access to said local lines and to said local switches, and means including trunk connections whereby any local switch may seize said toll line. 90
30. In a telephone system, local switches arranged to extend connections from local lines entering a telephone exchange, and a toll line entering said exchange and terminating in a toll switch having access to said local lines and to said local switches. 105
31. In a semi-automatic magneto exchange wherein a calling subscriber signals the operator by ringing current when he desires a connection set up from his line to the line of another subscriber, switching mechanism controlled by the operator to set up a connection from a calling line to a called line, and means associated with said switching mechanism for automatically making a predetermined application of ringing current to the called line 110 to signal the called subscriber and for then placing the circuit in talking condition for the remainder of the connection. 120
32. In a party-line semi-automatic magneto exchange, wherein the operator is sig- 125

nalled by the calling subscriber by means of ringing current transmitted over the calling line, automatic switching mechanism under the control of the operator for setting up a 5 connection from a calling line to a called party line, and means associated with said mechanism for automatically placing ringing current on the called line in accordance with a code pre-assigned to the called station and for then automatically placing the 10 established connection into talking condition for the remaining time that the connection is established.

33. In a party line, semi-automatic magneto exchange, wherein the operator is signalled by the calling subscriber by means of ringing current transmitted over the calling line, automatic switching mechanism under the control of the operator for setting up a 15 connection from a calling line to a called party line, and means associated with said mechanism for automatically placing ringing current on the called line in accordance with a code pre-assigned to the called station and for 20 then automatically placing the established connection into talking condition for the remaining time that the connection is established, said ringing means being effective to make a preliminary application of ringing 25 current to the called line before the said code application so as to attract attention and cause the subscribers to listen to the application of code ringing current.

34. In a telephone system, a link circuit, 35 a ringing-current-selecting device, individual to said link circuit, switching means whereby either end of said link circuit may be connected to a subscriber's line, and means in said link circuit whereby the ringing current 40 sent selected by said selecting device may be sent out to a connected subscriber's line over either end of the link circuit.

35. In a party line semi-automatic telephone system wherein automatic switching mechanism under the control of operators is 45 provided for setting up connections to and from party lines, means normally effective for transmitting ringing current over an established connection to a called line to signal 50 the desired station thereon, and means effective in case the switching mechanism is set in a predetermined position not corresponding to any particular called line for transmitting the ringing current in the reverse direction 55 to signal a called station on the calling line.

36. In a semi-automatic telephone system 60 wherein automatic switching mechanism in a central exchange is controlled by impulse series transmitted from an operator's switch-board to set up connections from and to party lines, means effective in case the called party is calling another party on the same line for transmitting ringing current to the calling line responsive to the transmission of an impulse combination bearing no relation to the 65

particular line, followed by impulses representing the designation of the particular called party on the calling line.

37. In a telephone exchange system, magneto lines entering an exchange, trunk lines 70 in said exchange, switching apparatus in said exchange, ringing-current generators on said lines, means responsive to the operation of a ringing-current generator for operating said switching apparatus to connect the corresponding line with an idle one of said trunk lines, and means including a timing device for restoring said connection at the end of a predetermined interval.

38. In a semi-automatic magneto exchange 80 wherein the semi-automatic operator is signalled responsive to an application of ringing current received over a calling subscriber's line, automatic switching mechanism effective to set up connections from calling lines to 85 called lines under the control of the semi-automatic operator, means for releasing an established connection responsive to a further application of ringing current received over a calling subscriber's line, and means including a timing device for automatically releasing the connection at the end of a pre-determined time interval in case the last-named application of ringing current has not 90 been received.

39. In a semi-automatic magneto exchange 95 wherein the semi-automatic operator is signalled responsive to an application of ringing current received over a calling subscriber's line, automatic switching mechanism effective to set up connections from calling lines to 100 called lines under the control of the semi-automatic operator, means for releasing an established connection responsive to a further application of ringing current received over a calling subscriber's line, and means including a timing device for automatically releasing a connection at the end of a pre-determined time interval, measured from the 105 completion of the connection, by releasing the connection in case the last mentioned application of ringing current has not been received.

In witness whereof, I hereunto subscribe my name this 17th day of June, A. D. 1927.

LEONARD L. RUGGLES. 115
